UNITED STATES PATENT OFFICE.

JOHN CLARK AND ALBERT HOEFT, OF CHICAGO, ILLINOIS.

DESIGN FOR A GAS-BURNER.

SPECIFICATION forming part of Design No. 33,554, dated November 13, 1900.

Application filed October 10, 1900. Serial No. 32,654. Term of patent 3½ years.

To all whom it may concern:

Be it known that we, JOHN CLARK and ALBERT HOEFT, citizens of the United States, residing at Chicago, in the county of Cook and State of Illinois, have invented and produced a new and original Design for Gas-Burners; and we do hereby declare the following to be a full, clear, and exact description of the same, reference being had to the accompanying drawing, forming a part thereof.

This invention relates to a design for a new and original gas-burner.

As shown in the drawing, the invention comprises a vertical circular central portion A, having the outwardly and downwardly tapered portion B connecting with the bead or flange C, in turn connected to a second vertically-disposed circular portion D, arranged at a point slightly inwardly from the outer edge of the beaded portion C. On the interior of the portion D is suspended a ring E through the medium of a cross-bar F; an

annular space G being left between the portion D and the ring E. From the lower edge of the ring E there is an inturned portion e. 25 The design is slightly broken away to better illustrate these last-mentioned features.

The essential feature of the design is a circular member having a tapered upper portion, together with an internally-arranged ring, 30 with the connecting cross-bars therebetween.

Having thus described the invention, what is claimed as new, and desired to be secured by Letters Patent, is—

The design for a gas-burner, substantially 35 as shown and described.

In testimony whereof we affix our signatures in presence of two witnesses.

JOHN CLARK.
ALBERT HOEFT.
